UNITED STATES PATENT OFFICE.

FRANTZ ADOLF MARTENS, OF COPENHAGEN, DENMARK, ASSIGNOR TO MARTENS' PATENT "TWISTING-IN" MACHINE CO., LTD., OF COPENHAGEN, DENMARK, A CORPORATION OF DENMARK.

MECHANICAL THREAD PASTING APPARATUS.

Application filed September 18, 1920. Serial No. 411,280.

To all whom it may concern:

Be it known that FRANTZ ADOLF MARTENS, subject of the king of Norway, residing at Thorvaldsensvej 20, Copenhagen, Denmark, has invented new and useful Improved Mechanical Thread-Pasting Apparatus, of which the following is a specification.

Joining the threads of old and new warps for textile fabrics may be performed either 10 by hand, the threads being knotted together two and two or—far more efficiently—by mechanical means, the thread ends being approached to one another and interconnected, for instance pasted together, by means of 15 suitable apparatus.

The heretofore known pasting devices of the kind here referred to are subject to the drawback, however, that the adhesive (the glue) cannot easily be dried and, for that 20 reason, quite complicated arrangements have to be made in order to isolate from each other, by means of paper strips or the like, the individual pairs of threads until the glue has become dry. Later on these paper strips 25 and the like have to be removed again.

According to the present invention, this drawback is remedied by the pasting together of the threads in pairs being effected practically instantaneously, the adhesive being supplied, to the place of contact between 30 the two threads to be pasted together, in quite small quantities (dropwise for instance) and dried in the course of a very short time, by passing the threads over a drying device which dries the paste by a 35 simultaneous action of heat and drying air.

These various operations are performed by means of a combined pasting and drying device driven by some motive power, and, 40 thereby, causing:

1. Only a drop of adhesive to be applied to the place of contact between the two threads to be pasted together,

2. This pair of threads immediately thereafter to be passed on to a gripping device which then,

3. Moves the thread on to the drying device, where,

4. Simultaneously the compressed air is admitted, whereafter,

5. The coupled thread is moved on, away from the drying device.

The warps extend crosswise, in well known

manner between cross-bars and the pasting and drying device and is moved in a direction across the warps, from the treated towards the untreated portion thereof. The necessary motions of the pasting and drying apparatus across the warps may be effected automatically by action of a suitable motive power.

The separation (isolation), from the remaining still untreated portion of the warp, of the individual pairs of threads to be pasted together may be effected, in the manner known from the British Patent specification No. 24749/1912, by means of a disc, the so-called heart, which is moved rapidly back and forth between the cross-beams in a direction parallel to the warp threads. It will be suitable to let this motion of the disc actuate the pasting and drying devices in such a manner that said disc while moving towards these devices, strikes special projecting members (levers, arms or the like) on said devices, by which means the latter partly will perform the above mentioned operations and partly will be moved across the warp so that their position relatively to the pair of threads to be pasted together always remains the same or at least approximately the same.

One embodiment of the invention is illustrated on the drawing, where—

Figures 1 and 2 illustrate diagrammatically the well known manner of stretching the warps in the joining machine.

Figs. 3 and 4 show in outline the threads stretched between the cross-bars, the heart (in central position) and the arrangement of the pasting and drying apparatus in side elevation and in top view, respectively.

Figs. 5 and 6 show the pasting and drying device in side elevation and plan respectively,

Fig. 7 is a cross-section of the same along the line I—I in Fig. 6, and

Fig. 8 is a detail of the same in side elevation.

Joining the threads of old and new warps for textile fabrics by mechanical means, is performed by stretching the ends of the old and new warp over cross-beams in a joining machine, and pasting together the threads concerned by means of a movable pasting device.

When the warp threads in a loom are nearly used, the ends of the said threads shall be connected with the ends of a new warp thread. The old warp is therefore brought directly together with the warp beam from the loom into the warp joining machine, and the old and new warp threads are then stretched out in the joining machine in the manner known from the British patent specification 24,749/1912 and shown diagrammatically in Fig. 1.

50 is the beam or roller with the old warp threads. The threads of this warp were in the loom separated into two layers by means of lease-rods, the said layers crossing one another. 51 represents the reeds and harnesses, which are removed from the loom together with the old warp. These members 51 are brought into the joining machine together with the old warp without being separated from the latter, and after being inserted in the said machine the old warp threads are stretched between the roller 50 and another roller 52. The cross beams 53, 23 are then inserted in place of the said lease rods between the warp threads, which are crossed at one point, so that the end of the old warp, stretched between the rollers 50 and 52, forms two layers of threads, crossing 30 one another between the intermediate beams 53, and each comprising every second of the said warp threads.

The roller 54 on which the new warp is arranged, is thereafter inserted in the joining machine, i. e., in the end of the same opposite to that end, where the roller 50 with the old warp is inserted, and the threads of the new warp are stretched between the roller 54 and another roller 55. When the threads 40 of the new warp are delivered from the warping machine, they are divided in two groups, alternate threads in a group, by leasing members, which after the new warp have been stretched in the joining machine, may 45 be replaced by cross-beams 56, so that the threads will form two separate layers, separated by the cross-beams 56 and crossing one another between the intermediate pair of beams 56 each comprising every second 50 thread of the new warp.

The cross-beams 53 are laid directly over the cross-beams 56 and brought close together, as shown in Fig. 1, so that the uppermost layer of the new warp and the lowermost layer of the old warp lie close together 55 after the insertion of the cross-beams 53 and 56.

The threads of the new warp are shown in dotted lines and the threads of the old warp in full lines in Figs. 1 and 2.

60 The threads of the two warps shall now be connected in known manner by pasting the threads together two by two. This is effected by pasting the threads 57 of the new warp to the threads 58 of the old warp at

the point 59 and by pasting the threads 61 of the new warp and the threads 62 of the old warp together at the point 60.

After effecting the connection of the warps the thread parts shown with thin lines in Fig. 2 are cut away and the new warp threads are drawn through the reeds 51 by turning the beam 50, whereafter they may be withdrawn from the joining machine and inserted in the loom concerned. 75

In order to prevent any uneven distribution of the warp threads, along these rollers 50 and 54, from being transferred to the portion of the warps located between the cross-beams 53 and 56 and on the tightening rollers 52 and 55, this portion of the warps, after the latter have been stretched in the joining machine, before or after the insertion of the cross-beams, is combed by combs of a length being suitably made equal to the width of the warp. By means of these combs which are made of iron or the like the warp is combed in the direction from the rollers 50 and 54, respectively, towards the tightening rollers 52 and 55 respectively, until a uniform distribution of the warp threads over the entire width of the warp has been attained, whereafter the comb 81 remains stationary with its teeth in the warp, as close to the tightening rollers as practicable, thereby securing the preservation of the uniform distribution of the warp threads. If the warp threads are combed immediately after they have been stretched on the cross-bars concerned in the manner shown in Figs. 1 and 2, the result is attained that the correct location of the warps on the said bars may be attained considerably quicker than heretofore. 100

In Figs. 3 and 4, 63 is a disc—the so-called heart—by means of which the selection of the threads of the two warps is effected, in the manner described in British Patent No. 24,749 of 1912. The said disc 63 may easily be shifted in the direction across the warp along a shaft 70 which is mounted transversely to the warps and has such a shape that the heart cannot revolve about the shaft. The latter and, thereby, also the heart are moved, in a direction parallel to the warp threads by means of cranks or the like (see British Patent No. 24749/1912), back and forth between that pair of cross-beams 53—56 between which the threads 57 and 61 respectively and 58 and 62 cross one another. 110

The heart 63 is in the manner described in the British patent specification No. 24,749 of 1912, or in any other suitable manner, pressed against the still untreated portion of the warps (in Fig. 4) upward so that the reciprocating motion, in combination with the special manner in which the threads are stretched will have the effect that for each individual stroke of the heart two threads will be separated in known manner from the 120

remaining still untreated portion of the warp, namely one thread alternately 58 and 62 from the old warp and one thread alternately 57 and 61 from the new one. The 5 place of contact 59 and 60 between such two corresponding threads will then be located alternately at the right hand and the left hand cross-beams 53, 56, (right and left in respect to Fig. 3), and the pasting of the 10 threads must therefore also be effected alternately at one and the other side of the apparatus, that is to say pasting and drying devices must be provided on both sides of the apparatus.

15 64 indicates these pasting and drying devices, and 65 indicates devices for supplying the drying air.

20 Each pasting device 64 consists essentially of a glue container 4 with one or more holes 67 to squirt the glue, a gripping device 90 and a heating device 5 (for instance a heating drum).

25 The position of the pasting device relatively to the warp threads is such that the pair of threads which is nearest to the rear side of the heart (that is the side of the heart which is resting against the not yet treated warp threads), and which is to be pasted together by the next following motion of the heart, comes directly over the glue holes 67. During the motion of the heart towards that pair of cross-beams 53, 56 where the gluing of the two threads concerned is to be performed, a drop of glue 30 will be pressed out in a manner more fully described hereinafter, through the holes 67 on the point 59 or 60 of the threads. During the continued motion of the heart towards the cross-bars, this pair of threads will now 35 be seized by an arm 66, which is pivoted to the heart, and will be transferred by this arm to the gripping device 90 just when a roller 68 journaled on a projection 69 on the arm 66 in known manner strikes the cross-beams and, thereby, turns the arm 66.

40 The gripping device remains as described more fully below at rest temporarily, but a spring which will be further mentioned in the following and which is tightened by the heart during the above mentioned motions of the latter will cause the gripping device to be turned a certain adjustable distance forward, immediately after the heart has 45 commenced its return motion, and the pasted pair of threads is now transferred to the heating drum 5 by the said gripping device.

45 Here the threads remain until the heart, during a subsequent forward motion, nearly simultaneously with the expulsion of the glue for the next pair of threads to be pasted on the same side of the machine gives access for the compressed air through the air supply device 65, which air in combination with the action of the heat now causes the glue 55 to be solidified almost instantaneously.

When subsequently the heart 63 moves back again, the gripping device is released once more, the pair of threads considered are moved further on, away from the drying device 5 where now the next following pair 70 will occupy the vacant position and so forth.

All these various operations, however, are performed in very quick succession, and alternately at the right hand and left hand side of the apparatus.

75 The compressed air may be supplied in any suitable manner. In Fig. 3 there is indicated an arrangement serving this purpose. It consists of a mouth piece 71, which is disposed centrally over the heating member 5, and has one or more downwardly directed holes, and is inserted, by means of a knee tube 65, in a holder 72 which is adapted to slide in a slot 74 passing longitudinally through the upper ones of the cross-beams 53. The compressed air is supplied to the hollow holder 72 by means of flexible tubes, 80 hoses or the like, which lead to a container of compressed-air arranged in any suitable manner outside the joining machine. The 85 holder 72 is fitted with a projecting wing 73 which projects over the path of the heart 63, Fig. 3, and is cut off obliquely in such a manner that the heart 63, while moving towards the cross-beams concerned and occasionally striking the slanting face of the wing, automatically takes the entire compressed air device along towards the still 90 untreated portion of the warp.

95 The action of the heart on the pasting devices is effected by means of members similar to the ones described above in case of the compressed air device and as further mentioned below, that is to say, during the forward motion the heart is pressed against levers 19, Fig. 4, pivoted resilient arms or similar members provided on the pasting devices, the depression of these members causing the performance of the above explicitly described operations and the occasional motion of the pasting devices across the warp in accordance with the motion of the heart in the same direction. This last mentioned motion may for instance be effected by means of pawls engaging the racks 100 105 110 115 120 125 130 75, Fig. 3, in the bottommost cross-beams 56.

Figs. 5 to 8 show a complete pasting and drying apparatus.

On a bracket 1 on a common bottom frame 2 there is fastened an oblong frame 3 in which there is inserted a detachable glue container 4 and a rotary heating drum 5. The shaft 6 of the latter passes out through the side of the frame 3 and supports here a ratchet wheel 7 which is fixed 125 on the shaft and which, by means of a rack 9 pivotally and resiliently disposed on a longitudinally movable driving rod 8, causes the drum to rotate step by step, as mentioned in the following. The object of this 130

rotation is to keep the surface of the drums clean, and, for this purpose, there is provided in a suitable manner a scraper device 12 (Fig. 6) which scrapes the solidified glue 5 from the drum during the rotation of the latter.

The drum is heated by an electric heating body which is placed therein and receives its current by way of contact rings 10 and 10 brushes 11.

In the glue container 4 there is provided a small pressure pump, which presses glue out through small holes 67 in the top face of the glue container. The pump is moved 15 by an arm 13 with adjustable stop 14 (Figs. 5 and 6). This arm 13 engages a slot 40 in the driving rod 8 and is driven by this rod.

The gripping device consists of a ratchet wheel 15 loosely journaled on the shaft 6 20 coaxially to the heating drum inside of the ratchet wheel 7 and being turned occasionally by means of an adjustable pawl 16 resiliently attached to the driving rod 8.

It appears from the above that the common driving rod 8 is what causes the various functions of the apparatus to be performed, inasmuch as it drives the pump, turns the heating drum and the gripping device, these motions being partly adjustable independently of one another.

The driving rod 8 performs a reciprocating (horizontal) motion during which it is guided in guides 17 and 18 on the frame 3 or on the common bottom frame 2.

The motion of the driving rod is effected 35 by the heart 63, Figs. 3 and 4, in the following manner:

A two-armed flat lever 19, 20 is journaled about a pin 21 attached to the bottom frame 40 2 and projects with its one long suitably shaped arm 19 into the space swept by the heart while the shorter arm 20 engages, by means of a pin, a slot 41 in an arm 22 on the driving rod 8.

A helical spring 23 fastened in the bottom frame presses against the bent wing 20 and holds the driving rod 8 and, thereby, also the lever 19 in the initial position, that is the position shown in Fig. 6, the end of the 50 long arm 19 of the lever resting then against a stop 24 in the bottom frame 2. While during its motion towards the pasting device the heart strikes the arm 19, it turns the latter inward and, consequently, displaces the driving rod 8 longitudinally as it appears plainly from Fig. 6.

The apparatus operates in the following manner:

While during its motion towards the 60 cross-bars the heart strikes the lever 19, the latter is depressed, and the driving rod 8 is then moved as mentioned above, the spring 23 being stressed. During this motion of the driving rod 8 the latter turns

first the arm 13 whereby the glue compressing pump inserted in the glue container 4 is actuated by an arm 25 which is provided in the vessel 4 and is connected to the arm 13. The said pump thereby presses a drop of glue up through the holes 67, Figs 3, 4, 70 5 and 6, which drop then adheres to the two foremost warp threads. During the continued motion of the heart, the displacement of the driving rod 8 is continued simultaneously with the roller 68 (Fig. 4) turning the arm 66 on the heart. The two threads thus moistened with glue are then, by means of the arm 66, moved towards the gripping wheel 15, in such a manner that they are caused to be placed in the wheel 15 80 in the position indicated by Z in Fig. 5. The threads are secured in this position by a spring 42, Figs. 3 and 5, fastened in suitable manner to the air-blowing device 71, so that this spring, when the arms 66 swing backward during the immediately following return motion of the heart, will prevent the threads from sliding out of the wheel 15.

When now the heart goes back, the lever 19, 20 is released as mentioned above and, consequently, the driving rod 8, and the latter slips back while actuated by the spring 23. The rack 9 journaled on the rod 8 thereby turns the heating body 5 a suitable short distance while the pawl 16 simultaneously advances the wheel 15, for instance four teeth forward. Hereby the gripping wheel 15 shifts the two glued threads from the position Z, Fig. 5, into a position in which the threads will be lying on the heating member 5, their mutual contact surface resting on the latter. The two threads previously lying at this place were immediately before exposed to an air jet from the nozzle 65, Fig. 3, and their glue was thoroughly dried by the action of the air jet and the heating, the heart having opened for the said air jet in the above mentioned manner at the same time as it shifted the driving rod 8. 42 is a spring which is secured to a suitable projection 80 on the air supplying device, and projects just over the gripping device 15 thereby securing the threads in proper position on the same.

During the next displacement of the driving rod 8, by action of the spring 23 that is at the next rotary motion of the gear wheel 15, the two threads are advanced further away from the heating drum 5 or will at least receive an impulse in that direction. It may happen, however, that the teeth of the gear wheel will not slip the threads and, consequently, takes the latter along in downward direction which might cause the threads to be severed.

In order to avoid this, there is provided, in close proximity of the wheel 15 a special thread detaching device, as shown in Fig. 8.

To a projecting arm 35 there is attached, adjustably, a curved arm 36 ending at the top in a fork in which there is inserted, rotatably, a lever 37 consisting of two links 37 and 39 and being fitted with a suitable adjustable counter-weight 38 tending to swing the arm 39 upward, the turning movement being relatively slight.

All these individual parts 36, 37, 38 are turned and adjusted relatively to each other in such a manner and arranged so that the wing 39 will press against the underside of the thread parts gripped by the gripping device. If the latter should try to take the threads along in a downward direction, the pressure of the wing 39 against the underside of the said threads will cause the threads to be removed from the rear wheel 15.

When the heart has moved, in known manner, so far in direction across the warps it strikes, besides the lever 19, also the head 34 on a lever arm 32. The displacement of the entire pasting device across the warp-threads is thereby effected by means of a pawl 26, which is sunk into one side of the bottom frame 2 and engages a rack 75. The said pawl 26 is journalled on an arm 28, which is pivoted about a pin 27 and is fitted with a slot 29, the latter being engaged by an arm 30, which extends through a passage in the lower part of the frame 2 (Fig. 5) and is secured to the shaft 31 to which the lever-arm 32 is fastened. A spring which is secured to the lower end of the shaft 31 presses the lever 32 against a fixed stop 33 on the bottom frame 2.

During the motion toward the cross-bars when the heart strikes the head 34 on the lever 32, the latter will be pressed inward towards the pasting device, whereby the shaft 31 is turned, so that a spring will be stressed, while the pawl 26 will press against the rack 75, thereby advancing the entire pasting device forward in direction across the warps.

By this movement the head 34 on the lever 32 moves away from the heart, thereby releasing the lever arm 32 and causing the shaft 31 to be turned backward by action of the spring. During said return motion of the shaft 31 the pawl 26 will slide on top of a number of the teeth on the rack 75 until the pawl returns to its initial position, shown in Fig. 5 in relation to the frame 2. The movement of the heart will therefore automatically cause the pasting apparatus always to occupy the proper position relatively to the warp threads.

The simultaneous action of heat and air on the glued portions of the threads is of paramount importance and is one of the main conditions of an efficient glued joint being attained. Heretofore this last mentioned feature has never been attainable in spite of numerous attempts in that direction.

I claim as my invention:

1. In a warp uniting machine having means for supporting two warps stretched mutually crosswise in the machine; a disc adapted to reciprocate parallel to the warps; a pasting device comprising means for supplying an adhesive to the thread of the warps; a heating member; and an air supplying device for blowing air upon the adhesive on the threads resting on the heating member. 75

2. In a warp uniting machine comprising a disc adapted to reciprocate parallel to the warps and select the threads in pairs one thread from each warp; a pasting device adapted to supply an adhesive to the threads; a heating member comprising a cylinder; and an air-supplying device for blowing air upon the adhesive on the thread resting on the cylinder to instantly dry the adhesive. 85

3. In a warp uniting machine; a frame; a lever pivotally mounted on said frame; a rod reciprocated by said lever, and a heating device, said rod in one direction operating a member supplying a paste dropwise to the warp threads and in the other direction advancing the thread toward the heating device. 90

4. In a warp uniting machine; a frame provided with a pivotally mounted lever and a slidably mounted rod a disc mounted in said frame and adapted to actuate said lever; a pivotally mounted heating member; and a gripping device actuated by said rod and directly connected to the shaft of the pivotally mounted heating member. 95

5. In a warp uniting machine; a frame; a member for supplying paste to the warp-threads located in said frame; a heating member pivotally mounted in said frame; a rod slidably mounted on the frame and engaging said paste supplying device and the shaft for said heating member; a lever pivotally mounted on the frame and adapted to actuate the rod; a second lever mounted on the frame and adapted to actuate means for advancing the combined pasting and drying devices and a gripping device connected to and actuated by said rod, said rod upon movement in one direction actuating a pasting device and upon movement in the other direction actuating the gripping and the heating devices. 110

6. In a warp uniting machine comprising a pasting device; a reciprocating disc adapted to select pairs of threads and carry them across the pasting device; a gripping wheel adapted to carry the thread over a heating device of said pasting device a ratchet wheel on the shaft of said gripping wheel; a rack cooperating with said ratchet wheel on the axis of said gripping wheel; a rod slidably supported by the pasting device and a lever engaging said rod and pivoted on the past- 120

125

130

6
ing device and adapted when actuated by the disc to cause the rotation of the gripping wheel, for removing the threads from the heating member.

5. 7. In a warp uniting machine comprising means for supporting two mutually crossed warps; a disc reciprocating parallel to the warps and adapted to select the threads in pairs; a pasting device for supplying adhesive to the threads; a heating member

comprising a cylinder and an air supplying device actuated by said disc and forming additional means for drying the adhesive.

In witness whereof I have hereunto signed my name in the presence of two subscribing witnesses.

FRANTZ ADOLF MARTENS.
